UNITED STATES PATENT OFFICE.

EDGAR H. GRANBERRY, OF JACKSONVILLE, ARKANSAS.

EXCAVATING-MACHINE.

1,308,351.

Specification of Letters Patent.

Patented July 1, 1919.

Application filed April 12, 1916. Serial No. 90,601.

To all whom it may concern:

Be it known that I, EDGAR H. GRANBERRY, a citizen of the United States, residing at Jacksonville, in the county of Pulaski and State of Arkansas, have invented certain new and useful Improvements in Excavating-Machines; and I do hereby declare the following to be a full, clear, and exact description of the invention, such as will enable others skilled in the art to which it appertains to make and use the same.

This invention relates to a ditching or excavating machine, and the primary object of the invention is to provide a device of this nature which is comparatively simple in construction, and which materially decreases the amount of labor contingent with the digging of ditching in fields.

Another object of this invention is to provide a ditching or excavating machine as specified, which includes a pivotally supported scoop, a conveyer for receiving the excavated soil from the scoop and a retaining bed for receiving the soil from the conveyer.

Another object of this invention is to provide a novel form of deflecting board and means for operating the same, upon which board the dirt will be deposited from the conveyer, and by regulating the position of the board, the dirt may be thrown into the rear end of the bed, intermediate portion or the front end, as desired.

Another object of this invention is to provide a retaining bed which has interchangeable bottoms, so that the soil may be retained in the bed and removed to any desired location prior to dumping, or a bed bottom which will deposit the soil upon each side of the ditch made by the machine.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like and corresponding parts throughout the several views, and in which:

Figure 1 is a top plan view of the improved excavating machine.

Fig. 2 is a side elevation of the machine, showing parts in section,

Fig. 3 is a cross sectional view through the machine,

Fig. 4 is a cross sectional view through the bed of the machine, showing the modified form of dumping bottom, and

Fig. 5 is a longitudinal section through Fig. 4.

Referring more particularly to the drawings, 1 designates the supporting frame of the excavating machine as an entirety, which is supported by suitable supporting wheels 2 which are mounted upon front and rear axles 3 and 4 respectively.

The supporting frame 1 has depending ears 5 secured to the under surface of the same intermediate of its ends, to which ears are connected rods 6. The rods 6 extend downwardly and forwardly from the ears 5 and are pivotally connected to the sides of a scoop 7 which is positioned beneath the structure slightly in the rear of the front wheels 2. A chain 9 is connected to the scoop 7 and it passes upwardly over a guide pulley 9^a. The upper end of the chain 9 is connected to a rod 8, which rod is in turn connected to the lower end of a pivoted hand lever 10. The hand lever 10 is pivoted at 11 to one side of the retaining bed 12 and it has a dog mechanism 13 carried thereby which co-acts with a quadrant 14 for holding the lever in various adjusted positions. The swinging movement of the lever 10 will move the rod 8 longitudinally, and either raise or lower the scoop 7, depending upon the direction in which the lever is swung.

The scoop 7 has a shaft 15 carried by the rear end edges of the sides of the same, about which a conveyer 16 travels. The conveyer 16 extends upwardly and rearwardly from the shaft 15 and travels about a shaft 17 carried by the bed 12. The shaft 17 is operatively connected to a stub shaft 18 by means of a gear 19 and pinion 20, which pinion is carried by the stub shaft. The stub shaft 18 has a sprocket 21 mounted thereon about which a sprocket chain 22 travels. The sprocket chain 22 also travels about a sprocket 23 which is carried by one of the rear wheels 2 for synchronous rotation therewith, which provides means for operating the conveyer 16 by the travel of the excavating machine.

The retaining bed 12 has a shaft 25 rockably carried thereby, which shaft has a deflecting board 26 secured thereto. The de-

flecting board 26 is positioned beneath the delivery end of the conveyer 16, so that the soil falling from the conveyer will fall upon the board 26. The shaft 25 has a crank arm 27 formed thereon, which is pivotally connected to an arm 28. The arm 28 is pivotally connected to the lower end of a hand lever 32, which lever carries a dog mechanism 33. The dog mechanism 33 co-acts with a quadrant 34 for holding the hand lever 32 in various adjusted positions. By swinging the lever 32, the crank arm 27 will be rocked for rocking the shaft 25 and altering the angle or incline of the board 26, so that the soil deposited upon the board by the conveyer 16 may be deflected or thrown toward the rear end, the intermediate portion, or the front end of the bed 12, depending upon the position of the board 26.

20 The sides 36 and 37 of the bed 12 are provided with inwardly extending transversely disposed flanges or strips 38 and 39, which are arranged in pairs for forming guides for the edges of the removable bottom 40 of the bed. Any suitable type of dump bottom may be employed in lieu of the bottom 40, as illustrated in the drawings, if so desired, without departing from the spirit of this invention.

25 The ends 41 and 42 of the bed 12 are provided with alining openings 43, through which a rod 44 may be inserted. The rod 44 extends longitudinally through the center of the bed 12 and is provided for supporting the dirt sheds or deflectors 45 and 46. The sheds 45 and 46 have metallic plates 47 and 48 secured to their upper edges respectively, and extending throughout their entire length. The plates 47 and 48 are provided with curved portions 49 and 50 respectively. The curved portion 49 is provided for resting over the upper surface of the rod 44, while the curved portion 50 of the plate 48 rests upon the outer surface of the curved portion 49, thereby supporting the sheds 45 and 46 by the rod 44. The sheds 45 and 46 extend downwardly from the rod 44 and outwardly therefrom, at an angle, as clearly shown in Fig. 4 of the drawings, and they are held against accidental swinging movement by means of hooks and chains 51 and 52, the hooks being secured to the sides 36 and 37, or by any analogous structure desired. The sheds 45 and 46 have their outer surfaces positioned inwardly short distances from the inner edges of the lower guiding strips 39, so as to permit the dirt which is deposited within the bed 12, by the conveyer 16, to travel down their outer surfaces, and be deposited alongside of the ditch which is formed by the scoop 7. The chains 51 and 52 and the hooks associated therewith, together with the plates 47 and 48, provide means whereby either of the sheds or deflectors 45 and 46 may be adjusted independ-

ently of the other deflector for the purpose of directing a greater or less amount of the soil to either side of the ditch preferred, to suit conditions.

A seat 60 of ordinary construction is 70 yieldably supported above the bed 12 and the levers 32 and 10 are positioned in close proximity to the seat, so that the operator of the device may conveniently reach them.

Any suitable means may be employed for 75 propelling the excavating or ditching machine.

From the foregoing description taken in connection with the accompanying drawings the advantages of construction and the 80 method of operation of the improved excavating machine will be readily apparent to those skilled in the art to which this invention appertains and, while in the foregoing description, the principle of the operation of 85 this invention has been described together with various features of construction, it is to be understood that certain minor features of construction, combination and arrangement of parts may be altered to suit practical conditions provided such alterations are comprehended within the scope of what is claimed.

What is claimed is:—

1. In a ditching machine, a substantially 95 rectangular dirt receiving body having its bottom open, excavating means carried thereby and projecting forwardly of the body, means operable longitudinally of the body for discharging earth from the excavating 100 means into the same, a shaft extending longitudinally of the body and disposed centrally thereof, oppositely directed downwardly and outwardly inclined deflectors rockably mounted at their upper edges upon 105 said shaft, the deflectors extending through the bottom of the body so as to direct soil delivered upon the upper faces of the deflectors laterally of a ditch formed by the excavating means, and means for adjusting 110 said deflector about the shaft so as to vary the distance at which the soil is deposited from the ditch.

2. In an excavating machine, a substantially rectangular body open at its bottom, excavating means carried by the body and projecting forwardly thereof, a delivery conveyer operable longitudinally of the body for delivering soil into the same from the excavating means, a shaft extending longitudinally of the body centrally thereof, two downwardly divergent deflectors, said deflectors extending through the bottom of the body and projecting laterally thereof and having their upper edges connected to the 120 shaft so as to be rockably supported thereby, the deflectors being capable of independent adjustment about the shaft, and means for securing said deflectors in independent adjustment.

3. In an excavating machine, a body having its bottom open, excavating means carried thereby and projecting forwardly of the body, a shaft extending longitudinally 5 of the body centrally thereof, downwardly divergent deflectors extending through the bottom of said body and projecting laterally thereof, arched supporting plates secured to the upper edge portion of said deflectors and fitting about the upper portion 10 of said shaft in superposed relation so as to permit independent adjustment of the

deflectors about the shaft, means for securing said deflectors in adjustment, and means for delivering soil from the excavating 15 means into the body onto the upper faces of said deflectors.

In testimony whereof I affix my signature in presence of two witnesses.

EDGAR H. GRANBERRY.
